CLAIM

The ornamental design for a periodontal analyzer, as shown and described.

DESCRIPTION

FIG. 1 is a front perspective view of a periodontal analyzer showing our new design;

FIG. 2 is a front elevational view thereof;

FIG. 3 is a side elevational view thereof;

FIG. 4 is an opposite side elevational view thereof;

FIG. 5 is a rear elevational view thereof;

FIG. 6 is a top plan view thereof;

FIG. 7 is a bottom plan view thereof;

FIG. 8 is a front perspective view of a second embodiment thereof, the second embodiment is similar to the first embodiment except for the detached clip for the dental instrument.

The broken line drawing of a table in FIG. 8 illustrative purposes only and forms no part of the claimed design.

FIG. 1

FIG. 2

FIG. 4

FIG. 3

FIG. 5

FIG. 6

FIG. 7

FIG. 8
